FIG. 1

FIG. 2

FIG. 3

FIG. 4

FIG. 5

FIG. 6

Figure 1 is a perspective view of a storage battery container, showing my new design.

Figure 2 is a side elevational view, to a reduced scale of one side of the storage battery container.

Figure 3 is an end elevational view, to a reduced scale of one end of the storage battery container.

Figure 4 is a top plan view thereof.

Figure 5 is a side elevational view, to a reduced scale of the other side of the battery.

Figure 6 is an end elevational view, to a reduced scale of the other end of the battery.

The bottom, not shown, is conventional.

The drawing figures are stippled to indicate contrast in appearance.

I claim:

The ornamental design for a storage battery container, as shown and described.
